VENTED PARACHUTE

Christian A. Volf, Los Angeles, Calif.

Application May 21, 1942, Serial No. 443,960

6 Claims. (Cl. 244—142)

1

This invention is a parachute, provided with vents opening automatically to relieve excess pressure existing below the canopy of the parachute.

Parachutes provided with vents have heretofore been proposed as, for example, in the patent to Malmer 1,777,441, dated October 7, 1930, and Tricau 1,862,247, dated June 7, 1932. However, I have found that if some or all of the panels forming the canopy are provided with diagonally extending, automatically opening vents, the performance of the parachute is greatly improved.

In the preferred form of the invention, the diagonal vents are arranged in end-to-end formation, thereby forming a zig-zag row extending laterally around the canopy. In another form of the invention, only every other panel is provided with a vent, the intermediate panels being of standard construction.

As noted above, the vents open automatically to relieve excess air pressure existing below the parachute. This property is particularly valuable at the moment of opening the chute, which opening ordinarily gives quite a shock to the parachutist, due to the sudden checking of the descent. This shock is considerably lessened, according to this invention, by the use of the described vents, which allow excess air pressure to escape progressively as the pressure builds up. The vents progressively close at the pressure decreases, so that the checking of the parachutist is distributed over a longer time and therefore there is less shock.

Furthermore, a parachute provided with the vents as described oscillates less and descends more nearly vertically, that is, with less lateral drift than with the ordinary parachute. It opens very quickly and even with varying loads its rate of descent does not vary more than about five feet a second.

The invention will be further described in connection with the accompanying drawings, in which

Fig. 1 is a plan view of a parachute according to this invention;

Fig. 2 is a side view;

Fig. 3 is an enlarged fragmentary view of a detail;

Fig. 4 is a perspective view showing the parachute just after landing; and

Fig. 5 is a plan view of a modification.

In these drawings, the canopy 2 is composed of a number of triangular panels 4, defined by load lines or cables 6, which converge to the

2

apex of the chute, which apex is provided with the usual air escape opening 8.

Each panel 4 is provided intermediate its ends with a diagonally extending vent 10. Considered in plan, as in Fig. 1, the vents 10 are approximately at 45° with respect to the lines 6. However, this angle may be varied, as desired. Each vent is formed by providing adjacent edges of the panel which define the vent with a suitable reinforcement 12, as by a strong hem which may enclose a reinforcing cord, the ends of which are secured to the cords 6 of the respective panels. The edges of the vent are usually fairly close together.

15 The vents are arranged in end-to-end formation and thereby form a zig-zag row extending around the parachute, as shown in Figs. 1 and 2. Shroud lines 14 of the usual type connect to the harness 16 for the parachutist.

20 Other shroud lines 15, secured at their upper ends as at 15', are secured to a ring 17; from this ring heavy elastic straps 19 extend to the harness 16. Cords 15 are particularly useful in opening the chute; they are tensioned before the cords 14 are tensioned, because of the contraction of elastic cords 19 and flatten the center of the chute and so aid in opening it.

25 Referring to the modification shown in Fig. 5, every other panel 18 is provided with a vent 20, the vents in plan being angularly positioned at about 45° to the lines 6, the vents preferably being arranged all at the same angle. The intermediate panels 22 are not provided with vents.

30 By reason of the use of diagonal vents, there is formed an air escape zone Z, of substantial horizontal area, extending both radially and circumferentially of the canopy, this zone Z being defined between concentric circles Z₁ and Z₂ passing approximately through the outer and inner ends of the vents 10 or 20, Figs. 1 and 5.

35 The described vents will open readily when the air pressure existing below the canopy exceeds a certain amount. This opening is progressive, in that the greater the pressure, the greater the opening. This is particularly valuable in easing the shock of descent, the vents opening wide when the parachute is first opened and therefore descending very rapidly. As the chute spreads the vents are wide open and so the descent is not checked too suddenly. As the parachute slows down, the pressure decreases and the vents gradually close, until a normal rate of descent is reached.

40 45 50 55 The chute of the present invention also descends with very little lateral drift and after

landing can be quickly collapsed so that the chutist is not dragged along the ground.

While the preferred embodiments of the invention have been described in some detail, it should be understood that the invention is not limited to such details, but may be carried out in other ways.

I claim as my invention:

1. A parachute comprising a canopy composed of panels, defined by upwardly converging load lines, certain panels being provided with diagonally extending vents extending diagonally from one load line to the next adjacent load line, positioned between the apex and the outer edge thereof, which vents open and close automatically and gradually upon increase and decrease of air pressure below the parachute said vents forming a pressure relief zone extending both radially and circumferentially with respect to the canopy.

2. A parachute comprising a canopy having a central opening at the apex thereof, the canopy being composed of triangular panels defined by reinforcing load lines converging to said central opening, each panel being provided with a diagonally extending vent extending between adjacent pairs of said load lines, said vents being arranged in end-to-end formation to form a zig-zag row extending circumferentially around the canopy, said vents opening automatically to relieve excess air pressure existing below the canopy.

3. A parachute comprising a canopy composed of panels defined by upwardly converging load lines and having a central opening at the apex thereof, every other panel, between its outer and inner ends, being provided with a diagonally extending vent extending diagonally from one load line to the next adjacent load line, all said vents being positioned in the same relative angular position in their respective panels, said vents opening and closing automatically upon increase and decrease of air pressure below the parachute said vents forming a pressure relief zone extending both radially and circumferentially with respect to the canopy.

4. A parachute comprising a canopy including panels defined by upwardly converging load lines, said canopy being provided with diagonally extending air escape vents extending diagonally from one load line to the next adjacent load line positioned intermediate the outer edge and the apex said vents being arranged in end-to-end formation to form a zig-zag row extending circumferentially around the canopy, shroud lines extending from the outer edge of the canopy to a body harness, additional shroud lines attached to the underside of the canopy at points adjacent said vents, and extending to a ring above said harness, and means attaching said ring to said harness.

5. A parachute comprising a canopy including panels defined by upwardly converging load lines, said canopy being provided with diagonally extending air escape vents extending diagonally from one load line to the next adjacent load line positioned intermediate the outer edge and the apex said vents being arranged in end-to-end formation to form a zig-zag row extending circumferentially around the canopy, shroud lines extending from the outer edge of the canopy to a body harness, additional shroud lines attached to the underside of the canopy at points adjacent said vents, and extending to a ring above said harness, and means attaching said ring to said harness.

6. A parachute comprising a canopy having a central opening at the apex thereof, the canopy being composed of triangular panels defined by reinforcing load lines converging to said central opening, every other panel being provided with a diagonally extending vent extending between adjacent pairs of load lines, said vents extending circumferentially around the canopy, said vents opening automatically to relieve excess air pressure existing below the canopy said vents forming a pressure relief zone extending both radially and circumferentially with respect to the canopy.

CHRISTIAN A. WOLF.
